UNITED STATES PATENT OFFICE.

OWEN J. McGOWAN, OF BROOKLYN, NEW YORK.

RELEASING-HOOK.

1,308,549.

Specification of Letters Patent.

Patented July 1, 1919.

Application filed December 31, 1918. Serial No. 269,098.

To all whom it may concern:

Be it known that I, OWEN J. McGOWAN, a citizen of the United States, and a resident of the borough of Brooklyn, city of New York, in the county of Kings and State of New York, have invented certain new and useful Improvements in Releasing-Hooks, of which the following is a specification.

10 This invention relates to releasing hooks, for sustaining, transferring and releasing various loads; and the invention is particularly adapted to use with ships' davits for raising and lowering life boats. The invention, however, is not confined to use with davits and life boats, but is adapted to be used in handling loads of all kinds, and I therefore, in the drawings which accompany the specification, show two arrangements of 15 the hooks, first, in connection with a life boat, and second, an arrangement for use in raising, lowering and transferring other loads.

The hook is characterized by a body part, 20 or "housing", in which is housed, or pivoted, the hook proper, which has a small independent movement to and fro in the housing for locking said hook proper in and unlocking it from said housing. Said hook proper, (which hook proper hereinafter I generally designate simply as the hook) also has a free pivotal motion, when unlocked from said housing, in a plane which, when the hook is used with a life boat, is longitudinal of the boat, and said free pivotal motion of said hook trips the hook and releases the boat automatically; said hook being so weighted, by reason of its shape, as to be normally overbalanced, so that when the 25 strain of the load of the life boat is removed from the hook, as when the boat is water-borne, the hook automatically trips and releases the boat. The body part, or housing, of said hook is also preferably pivoted to the upper end of the rods, or other devices, by which the hook is secured to the boat, so that said hook swings in the longitudinal plane of the life boat from both 30 ends, and inwardly toward the middle of said boat; this motion of the body or hook falling as a whole in a fore and aft direction, also tending to insure the freeing of the hook from the boat tackle blocks, as will be hereinafter more fully explained.

35 Another important feature of this invention is a key or wedge, which, when in-

serted by hand in the proper position in the housing, locks said hook so that it cannot open and release the boat from the tackle. Thus the accidental release of the life boat 40 from the davits, at improper times, which might otherwise occur, is prevented. Said wedge or key is preferably secured to said hook by a flexible connection, at the point farthest out from the pivot of said hook, 45 and where the weight of said wedge or key is most efficient in helping to trip the said hook when said key or wedge is withdrawn, and the hook is free to trip. In use said wedge or key is always inserted in the housing 50 when the boat is being raised from the water, so as to lock the hook to the tackle, and said wedge or key is always withdrawn from the housing, and the hook is left free to turn and release the boat from the davit 55 tackles when the boat is being lowered to the water.

The hook, as used with life boats, can also be used with various other loads; but I prefer, when using said hook with other loads, as in mines where the rise and fall of the load is great, or in cases where great loads are handled, to arrange the hook in the reversed position from that in which it is placed when used with life boats—that 60 is to say, the hook is now turned downward and so as to lie beneath the shackle, ring or other members which connects the hook with the load, and so that the hook now sustains the load, and the wedge or key is 65 now arranged above the pivot of the hook. I also prefer to make certain other slight changes in the form and arrangement of the hook, when it is used for other loads, as will be hereinafter more particularly explained. 70

In the case of all the hooks, whether for life boats or other loads, great attention is given to shaping the housing and the hook with long easy curves, so that neither the life boats nor any parts of any loads or apparatus connected therewith, shall catch on the hooks and tend to obstruct them or operate them improperly, but that the hooks will always glide clear of any obstruction. This feature of the hook is hereinafter more fully 75 described.

Referring to the drawings which accompanying the specification, Figure 1 is a broken elevation of the invention applied to a life boat and davits; Fig. 2 is a broken 80 side elevation and section of a hook in locked position, and with the locking wedge or key

in place in the housing, so as to lock the hook against accidental displacement; Fig. 3 is a broken sectional elevation showing several of the same parts as are shown in Fig. 2, but with the hook open; Fig. 4 is a broken front sectional elevation of the hook, as seen from the left of Fig. 2, but with the locking wedge removed.

Referring to Figs. 1, to 4 inclusive, A is 10 a life boat, and B and C the davits; D being the spreader, and E the continuous tackle. G—G are the hooks of the present invention, shown as preferably pivoted on the upper end of the suspending rods H—H, which are 15 provided with clevises at their lower ends which are secured to the keel K of the life boat, so that the entire weight of the life boat may, however, be connected with the life 20 boat in any other manner, and this invention is not limited to the manner in which the hooks are connected with the life boat.

Each of said hooks G is constructed and arranged as follows: There is a body part 25 or "housing" 1, which is preferably pivoted on the upper end of a rod H as hereinbefore stated, and so as to have a free pivotal motion on said rod in the direction of the longitudinal plane of the boat, and inwardly or 30 toward the center of the said life boat; the motion of said housing in the opposite direction being prevented by a stop 3. Said motion of said housing 1, tends to free the hook 6 from the eye or shackle e of the davit 35 tackle E, when said hook trips to releasing position.

Said hook is so formed or weighted, that, when said hook is unlocked, and ready to trip, it is overbalanced and falls away from 40 said shackle or eye e, and to the position of Fig. 3 wherein the end of the boat will be free from the davit tackles; and this, as will be understood, takes place when the boat is 45 being lowered and the end of the boat is water-borne. In this position, as will also be understood, the continuous tackle E pays from davit to davit, so as to release the strain on the hooks at both ends of the boat practically simultaneously, and so that the 50 boat falls freely to the sea. At the same time as the hook 6 opens and releases the tackle, the housing of said hook 1 falls inwardly and facilitates the releasing of the hook for said tackle.

55 Said hook 6 is pivoted at 7 in said housing 1, and the pivot hole 8 through said hook is somewhat elongated so that there is a slight vertical movement of said hook 6 in the said housing 1, in addition to its free 60 pivotal motion in said housing around said pivot 7. This capability of independent motion is an important feature of the invention, and is covered by several of the claims. The free end of said hook 6, is formed with 65 a locking tooth 9, which, in the locking po-

sition engages a head 10 formed with an undercut recess in the upper end of said housing 1. When the boat is being raised from the water, and also when it is being lowered to the water except when the boat is 70 water-borne, said hook is locked with said head 10 of the housing, but when the strain of the weight of the boat is off the said hook 6, as when the boat is water-borne, the motion of said hook 6 vertically in said housing 1, allows said locking tooth 9 to come clear of said head 10, and the hook 6 to come free from the eye or shackle of the tackle E. It will be seen that the locking and unlocking of the hook is effected by the 75 independent motion of said hook 6 on its pivot 7 in said housing 1. When connecting the boat to the davits for raising it to position on the ship, the strain of the davit tackles on said hooks 6 will cause said hooks 80 6 to turn inward and slide their teeth 9 into engagement with the head 10, and then a man in the boat will insert the keys 14 in said housings under the cam shaped ends of said hooks 6, and will thereby lock said 85 hooks against accidental displacement.

The lower ends of said hooks 6 are formed as a flat curved cam 12, and there is a space through said housing under and immediately contiguous to said hook when in the 90 locked position in which is inserted a key or wedge 14, when the said hook is to be locked, and which wedge or key then presses tightly up against said cam 12, so as to prevent unlocking said hook 6. When the boat is being raised from the water, and when it is swinging from the davits, said key is always 95 in place in said housing, so as to hold said hook 6 in the locked position and against the accidental unlocking of said hook, and the releasing of the boat from the davit tackle; but when the boat is being lowered to the sea, and before it begins to be lowered, said key 14 will be drawn out of said housing 1, and said hook 6 will be free to turn 100 to its unlocking position, and to release the boat from said davit tackle when the strain of the tackle on said hook is relieved, as when the boat is water-borne.

Both the housing 1 and the hooks 6 are 105 shaped at all parts of their contours, so as to present long easy curves that will not catch against projecting parts of the davit apparatus or the boat, or any other obstructions, but that said housing and hook will slide 110 freely past said obstructing parts without catching thereon, and so as not to be improperly caught or operated by said obstruction; and it will be understood that these long easy curves are characteristic not 115 only of the hooks which are used with life boats, but of hooks that are used with other loads.

The operation of the invention with davits and life boats will be clear from the foregoing 120

ing description, with but little additional explanation.

Assume that the boat is hanging from its davits, and with said keys 14 in the housings, so that said hooks 6 are locked. Now some accident occurs, and it is necessary to lower away a boat. Sailors at each end of said boat first draw out said keys 14 from the housings 1, so that said hooks 6 are free to turn. Then the boat is lowered away, the strain of the weight of the boat on the tackle holding the hooks still in locked position, and the boat lowers away practically on the even keel, until one end of the boat is water-borne. Then the continuous reaving of the tackle E from davit to davit insures that both hooks will be released from the strain of the tackle practically simultaneously. The hooks at both ends of the boat will therefore move slightly down, so that the tooth 9 of each hook will come clear of the locking head 10, and said hooks will then overbalance and open, releasing the eyes or other members which connect said hook with the blocks and tackle, and the boat will then fall to the sea practically on an even keel, and without danger of being capsized. The boat will then be rowed away from the ship. To return the life boat to the davits, the life boat being in position under the davits, and so as to be raised by the davit tackle, sailors in the life boat at each end take hold of the flexible connections 15 of each key, and raise them to practically vertical position. Then said hooks 6 are inserted in the eyes or shackles e of their respective davits, and said hooks are closed. The tackle E is then operated to lift the boat, and the strain of the tackle through said eyes e on the hooks 6, now holds said hooks in closed position. At the same time, sailors at the two ends of the boat push the keys 14 into their respective housings, and lock said hooks against accidental displacement. Now the boat is lifted by the davits to the deck of the vessel.

It will be understood that in all forms of the invention, said keys 14 are preferably connected with said hooks 6 by a flexible connection, as a chain 15, and it will also be understood that in the form of the hook that is used with life boats and davits, said flexible connection is preferably fastened to the hooks 6, and so that when said key is hanging freely from said hook, as seen in Fig. 1, the weight of said key 14 will be most effective to help turn said hook to its unlocked position.

It will be understood that the keys 14 and the chains 15 serve several important purposes: First, the chain is used for throwing the hook 6 to an upright position, and at the same time by the use of said chain the attendant raises the housing and hook as a whole to an upright position; second, the at-

tendant raises the hook proper 6 to engage the eye e of the block, this motion bringing the tooth 9 of said hook into locking engagement with the head 10 of the housing, so that the hook is now closed; third, when the weight of the boat is suspended on the tackles, the attendant inserts the wedge in the recess through the housing, thereby securely locking the hook against accidental displacement, until the boat is lifted to the ship's deck. In all these three movements, it will be understood the attendant at no time has to handle the hook to throw it in a locked position with the tackle, and danger of injury to the attendant's hand is eliminated.

It will be observed also, that this invention obviates the need of shackles, separate hooks and lanyards for housing the hook in connection with life boat detaching gears; the invention serving both as hook and shackle, and in this respect said invention effects considerable economy over the use of other hooks.

In all modifications of the invention, the fits of all the parts with each other are loose and easy, and the materials of the housings, hooks and pivot pins, are brass tobin and bronze diminish the danger of corroding and of sticking the parts of the hook so that they will not operate, and in fact the hook will remain in good operative condition for a long time.

Now having described my improvements I claim as my invention.

1. The combination in davit apparatus for raising and lowering life-boats of a body part and a hook adapted to be suspended from said davit apparatus and pivoted to said body part and capable of a small independent movement in said body part in addition to its pivotal motion therein whereby said hook is engaged with said body part to hold the hook in position to sustain the weight when said hook is locked and said hook is moved out of engagement with said body part when the strain of the weight comes off from said hook.

2. The combination in a releasing hook, of a body part and a hook overbalanced when said hook is in a released position so that said hook pivots to full open position, and said hook being pivotally connected with said body part and being capable of a slight motion independent of its pivotal motion.

3. The combination in a releasing hook, of a body part, a hook pivoted in said body part and capable of a slight independent motion in said body part in addition to its pivotal motion therein, and a locking key adapted to lock said hook against moving to releasing position when said key is inserted in said body part and adapted when said key is removed from said body part to permit

said hook to pivot freely to its full releasing position.

4. The combination in a releasing hook of a housing, a hook pivoted therein, and having a capacity for a slight motion independent of its pivotal motion, a cam shaped end on said hook, an aperture in said housing adjacent to said hook when said hook is in locked position, and a locking member 10 adapted when inserted in said aperture to lock said hook against movement.

5. The combination in a releasing hook of a housing, a locking head thereon, a hook pivoted in said housing and capable of a slight motion in said housing independent of its pivotal motion, and a locking projection on said hook adapted to engage with 15 said locking head of the housing in one position of the hook, so as to hold said hook

in the locked position and adapted in another position of said hook to permit said hook to pivot freely to its full releasing position.

6. The combination in a releasing hook, 20 of a housing, a hook pivoted in said housing and capable of a slight motion in said housing in addition to its pivotal motion therein, and a locking key adapted when inserted in said housing to lock said hook and prevent its motion, and a flexible connection 25 connecting said locking key with said hook.

Signed at New York city, in the county of New York, and State of New York, this 27th day of December, A. D. 1918.

OWEN J. McGOWAN.
